William Hucal, 3814 N. Wilton Ave.,
Chicago, Ill. 60613

Filed Apr. 7, 1966, Ser. No. 1,883

Term of patent 14 years

(Cl. D54—1)

FIGURE 4 is a bottom view of the metal clip, or similar article as it appears when assembled to the opposite ends of a round band, or metal wire, the dotted lines fragmentarily showing of the band being for illustrative purposes only.

I claim:

The ornamental design for a metal clip or similar article, as shown and described.
